Primary Examiner — David Muller(74) Attorney, Agent, or Firm — Jacobson Holman PLLC(57) CLAIM

I claim the ornamental design for the vent, as shown and described.

DESCRIPTION

FIG. 1 is a top perspective view of the vent embodying my design;

FIG. 2 is a bottom perspective view thereof;

FIG. 3 is a top plan view thereof;

FIG. 4 is a bottom plan view thereof;

FIG. 5 is a side elevation view thereof, the view of the other four sides being identical; and,

FIG. 6 is a cross-sectional view along line 6-6 of FIG. 3.
